UNITED STATES PATENT OFFICE.

GEORGE REHFUSS, OF PHILADELPHIA, PA., ASSIGNOR TO HIMSELF, AND J. GEORGE REHFUSS AND MARTIN O. REHFUSS, BOTH OF SAME PLACE.

DENTAL PLUGGER.

SPECIFICATION forming part of Letters Patent No. 271,986, dated February 6, 1883.

Application filed October 14, 1882. (No model.)

To all whom it may concern:

Be it known that I, GEORGE REHFUSS, a citizen of the United States, and a resident of Philadelphia, Pennsylvania, have invented 5 certain Improvements in Dental Pluggers, of which the following is a specification.

My invention relates to an improvement in dental pluggers similar in general construction and operation to that described in Patent No. 10 264,756, granted September 19, 1882, the present invention relating to a modification of that form of plunger adapted to be driven from an external shaft instead of by a spring carried by the instrument itself.

15 In the accompanying drawings, Figure 1 is a longitudinal section of sufficient of the plunger to illustrate my invention; Fig. 2, a transverse section of part of the same, and Fig. 3 a sectional plan view.

20 A is the tubular stem or hand-piece of the plunger; G, the plug-rod, and H the hammer for acting upon the upper end of said rod, this hammer being hung to a rock-shaft, m, which has pallets v, adapted to engage with the teeth 25 of the pallet-wheel M, so that as said wheel M is rotated a rapid vibrating movement will be imparted to the hammer and a series of blows delivered upon the plug-rod. In the patented instrument the wheel M was rotated by a 30 coiled spring acting through the medium of a system of gearing; but in the present case this spring and gearing are dispensed with, the instrument being intended for use in connection with the shaft of a dental engine or other 35 source of power.

The shaft may be connected directly to the projecting end of the spindle w of the wheel M; but as it is preferable to have the instrument in line with the shaft I provide the spindle 40 w with a worm-wheel, N, which is adapted to engage with a worm, K, on a shaft, x, the hammer and its operating mechanism being contained in a casing, B, at the end of the stem A, as usual, and the shaft x projecting from this casing, so as to be readily attached to the driving-shaft. That portion of the shaft x which is within the casing is adapted to 45 bearings a on an arm, b, the latter being pivoted to the casing at the upper end, and free 50 to swing at the lower end, so as to carry the worm into or out of engagement with the worm-

wheel. This movement of the arm is effected by means of a sliding tube, D, in the hand-piece, said tube having an inclined lug, d, adapted to act upon a similar lug, e, on the lower bearing, a, a spring, f, acting upon the upper bearing and tending to keep the lugs d and e always in contact with each other.

The sleeve D is similar to the locking and releasing sleeve D of the patented instrument above alluded to, and is operated in the same way, the sleeve being depressed in order to throw the worm K into gear with the worm-wheel when it is desired to operate the hammer, or being elevated so as to permit the worm 65 to be thrown out of gear with the worm-wheel when it is desired to stop the vibration of the hammer.

The force of the blow delivered by the plunger is regulated by the adjustment of a friction-spring, g, which bears upon one side of the plug-rod G, and is acted upon by a set-screw, h, adapted to a threaded opening in the tubular casing A, the friction of the spring upon the rod being governed by the adjustment of said screw.

The sleeve D is slotted for the reception of the spring, and the set-screw h is of tubular form, for the reception of a pin, n, which projects from the back of the spring, said pin preventing the spring from dropping out of place if the set-screw is entirely removed from the casing.

In carrying out my invention other means than the worm and worm-wheel may be employed for transmitting power from the shaft x to the spindle of the wheel M. For instance, a bevel-gear on the shaft may engage with a bevel-pinion on the spindle. The worm and worm-wheel are, however, preferred.

I claim as my invention—

1. The combination of the stem A and plug-rod G of a dental plugging-instrument with a pivoted hammer, H, a toothed wheel for operating the same, and a projecting shaft adapted 95 to be driven by power, and having a driving-connection with the spindle of said wheel, as specified.

2. The combination of the stem A, the plug-rod G, the pivoted hammer H, a toothed wheel, M, for operating the same, a projecting shaft adapted to be driven by power, and gearing

whereby said shaft is connected to the spindle of the wheel M, part of said gearing being carried by a swinging arm, whereby it can be moved into or out of operative position, as set forth.

3. The combination of the stem A, the plug-rod G, the pivoted hammer H, the toothed wheel for operating the same, the projecting shaft x, the gearing K N, the swinging arm b, having a lug, e, and the sliding tube D, having a lug, d, as set forth.

4. The combination of the stem A, the plug-rod G, a hammer for operating the same, a

spring, g, adapted to bear on the plug-rod, and an adjusting-screw, h, as set forth.

5. The combination of the stem A, the plug-rod G, a hammer for operating the same, the friction-spring g, having a pin, n, and the tubular set-screw h, as set forth.

In testimony whereof I have signed my name to this specification in the presence of two subscribing witnesses.

GEO. REHFUSS.
